UNITED STATES PATENT OFFICE

2,425,305

PRINTING DEVICE

Courtney Lee Comegys, University Heights, Ohio,
assignor to Addressograph-Multigraph Corporation, Wilmington, Del., a corporation of Delaware

Application April 29, 1943, Serial No. 485,039

4 Claims. (Cl. 101—369)

1

This invention relates to printing devices and particularly to those which may be used as printing and control devices.

A printing and control device of the character in which this invention may be embodied usually includes a carrier or frame that is desirably formed from sheet metal and which affords a flat face on which one or more printing plates may be releasably retained by suitable retaining devices formed on the body of the carrier. Such devices are also arranged in such a way that perforations or other data representations may be formed thereon so that when devices of this character are utilized in machines of the kind, for example, disclosed in Gollwitzer Patent No. 2,132,411 or No. 2,296,277, respectively patented on October 11, 1938, and September 22, 1942, data may be printed directly therefrom and under control thereof.

A device of the aforesaid character also usually has what is commonly referred to as an index card releasably retained on the face of the carrier thereof in association with the printing plate or plates and an impression is usually made on this card from at least selected of the type characters afforded on the printing plate or plates. In those instances where an index card of the aforesaid character has been provided heretofore and data representations in the form of perforations are included on the device, aligned perforations have been formed in the card and carrier at selected predetermined positions to thereby afford the data representations. In such instances when it is desired to change the data representations, the index card on the carrier has been removed and another card has been substituted therefor to thereby enable new data representations to be afforded by forming aligned perforations in the card and carrier. An arrangement of this general character is disclosed in Gollwitzer Patent No. 2,132,412, patented October 11, 1938.

The data representations that are afforded on a printing and control device of the character to which this invention pertains are usually related to at least selected of the type characters afforded on the printing plate or plates retained on the carrier and when a change in the data representations is to be made as, for example, in the manner just described, it is possible in arrangements of the aforesaid character to change either the type characters or the data representations without changing both since the type characters are included on a plate while the data representations are in part afforded in the card and since the plate and card are separately retained on the

frame, one may be changed without the other. Such an inadvertent failure to change both the plate and the card when a change is desired in both the data representations and the type characters to which these data representations are related may result in improper functioning of the device and it is, therefore, the primary object of my invention to insure that when a change is made in the data representations, a corresponding change will be made in the type characters, or vice versa.

More specifically, it is an object of this invention to afford data representations on a printing and control device by affording aligned perforations in the plate bearing the type characters to which the data representations are to be related and the carrier on which such plate is mounted so that when one plate is removed from the carrier and another is substituted therefor, both the data representations and the type characters will be changed.

Another and yet more specific object of this invention is to enable data representations and type characters to which such representations pertain to be related one to the other in a predetermined manner as by aligning the data representations and the type character to which such representations pertain.

Other and further objects of the present invention will be apparent from the following description and claims and will be understood by reference to the accompanying drawing which, by way of illustration, shows preferred embodiments and the principle thereof and what I now consider to be the best mode in which I have contemplated applying that principle. Other embodiments of the invention embodying the same or equivalent principle may be used and structural changes may be made as desired by those skilled in the art without departing from the present invention and the purview of the appended claims.

In the drawing,

Fig. 1 is an elevational view of a printing device embodying my invention;

Fig. 2 is an end view of the printing device shown in Fig. 1;

Fig. 3 is a sectional view taken substantially on the line 3—3 in Fig. 1;

Fig. 4 is an elevational view of a printing device embodying a modified form of my invention; and

Fig. 5 is a sectional view taken substantially on the line 5—5 on Fig. 4.

The printing device shown in Figs. 1, 2 and 3 of the accompanying drawing includes a frame or carrier F desirably formed from sheet metal

and affording a flat face on which in the present instance an index card C and two embossable printing plates P and P₁ are releasably retained. Thus, the card C is retained on the frame F by a bead UB formed along the upper edge of the frame and retaining devices as RD struck up from the face of the frame. The plate P has a notch formed in one end thereof adapted for cooperation with a retaining device RD₁ and retaining devices as RD cooperate with the longer edges of the plate P to retain it on the frame. A depressible tongue DT is provided for cooperation with the end of the plate opposite that cooperating with the retaining device RD₁ and when this tongue is depressed out of alignment with the adjacent end of the plate P, this plate may be slid from retaining devices RD and RD₁ adapted to cooperate therewith. The plate P₁ is retained on the frame F by retaining devices RD and RD₁ and a bead LB formed along the lower edge of the frame as well as by a depressible tongue DT₁, which like the tongue DT may be depressed out of cooperation with the adjacent edge of the plate P₁ to thereby enable this plate to be slid from the retaining devices RD and RD₁ and the bead LD. Thus the printing device shown in the accompanying drawing is arranged in much the same manner as is the printing device disclosed in Gollwitzer Patent No. 2,115,444, patented April 26, 1938.

Type characters as T and T₁ are respectively embossed on the plates P and P₁ and resort is desirably had to the utilization of two plates as P and P₁ since the data that may be printed from the type characters as T is usually relatively permanent, whereas that which may be printed from type characters as T₁ is usually somewhat transitory in nature in that this may change from time to time. It will be understood, however, that my invention may be embodied in a printing device including only a single plate as, for example, a printing device such as that disclosed in Gollwitzer Reissue Patent No. Re. 22,249, patented January 12, 1943. Thus, resort would be had to a printing device of the character disclosed in this Gollwitzer reissue patent in those instances where most if not all of the type characters on a particular printing plate would need be changed when a change was desired in the data that could be printed from such type characters and under control of data representations related to such type characters.

However, the printing device shown in the accompanying drawing is one from which a name and account number and the amount of an account may be printed and such data will remain more or less constant once a printing device of this character has been made up to be suitable for use. Moreover, the type characters T₁ in the present instance relate to deductions and the like and are to be made with respect to the amount represented by certain of the type characters T embossed on the plate P. These deductions may change from time to time and it is, therefore, advantageous to include these type characters on a plate as P₁ separate and apart from the plate bearing the type characters as T which relate to more or less unchanging data.

Furthermore, it is desirable that the data which may be printed from the type characters as T₁ be capable of being interpreted so that the data that may be printed therefrom may be entered into accumulators or utilized in other operations as, for example, in machines of the character to

which Gollwitzer Patents Nos. 2,132,411 or 2,296,-277 relate.

In order that data representations of this nature may be afforded on a printing device of the aforesaid character, data representations in the nature of perforations D and D₁ are formed in the plate as P₁ and the underlying portion of the frame F.

The type characters as T and T₁ may be embossed on plates as P and P₁ in an embossing machine of the character disclosed, for example, in Duncan Patent No. 1,518,904, patented December 9, 1924, and the perforations as D may be afforded in a plate as P₁ by the utilization of a punching machine of, for example, the character disclosed in Benes Patent No. 2,265,222, patented December 9, 1941, or, for example, like the punching machine disclosed in Gollwitzer Patent No. 2,265,229, also patented December 9, 1941. Particularly in those instances where the printing and control devices to which this invention relate are to be utilized in machines of the character disclosed in the aforesaid Gollwitzer Patents Nos. 2,132,411 and 2,296,277, the perforations as D will be formed in accordance with the code explained in these Gollwitzer patents. Moreover, since it is desirable that the sensing means adapted for cooperation with the aligned perforations as D and D₁ but capable of passing through such perforations, it would be desirable that the punching machine as disclosed in the aforesaid Benes Patent No. 2,265,222 or Gollwitzer Patent No. 2,265,-229 be modified so as to accommodate a frame as F when a plate as P₁ is mounted thereon for so to do will enable the aligned perforations to be formed in the plate as P₁ and frame F simultaneously. However, if desired, the entire area of the frame whereat perforations as D₁ may be formed, may be preperforated in the manner explained, for example, in Gollwitzer Patent No. 2,132,412 and when resort is had to such a preperforated frame, then it will only be necessary to afford perforations in a plate as P₁, for once a plate perforated at selected of predetermined positions is installed on a frame as F, that has been preperforated, the perforations as D in the plate as P₁ will be aligned with the proper perforations in the frame so that, therefore, the sensing means adapted for cooperation with such aligned perforations may freely pass therethrough.

In the form of my invention illustrated in Figs. 1, 2 and 3, the index point positions whereat perforations as D may be formed in a plate as P, are arranged in alignment with the positions on the plate whereat type characters as T₁ may be embossed thereon and when resort is had to an arrangement of this character the perforations as D may be formed in the plate as P simultaneously with the embossing of the type character to which such perforations are to be related and in order that this may be realized, resort may be had to a machine of the character disclosed in Glogaud et al. Patent No. 2,022,498, patented November 26, 1935.

In accordance with the well understood practice in the art, the frame F has index tabs as IT mounted thereon in, for example, the manner disclosed in Gollwitzer Patent No. 2,049,436, patented August 4, 1936, and if desired, shiftable tabs as ST may be provided on the frame as F in the manner disclosed, for example, in Gollwitzer Patent No. 2,080,417, patented May 18, 1937.

Moreover, in accordance with the well understood practice in the art, spacing flanges as SF are afforded on the back of the frame F for the

purpose of spacing the printing devices one from the other when the devices are stored in drawers or the like when not in use and when these devices are stacked in the magazines in the machines through which the printing devices are passed.

By referring to Fig. 1, it will be noted that selected of the data that may be printed from the type characters T on the plate P is printed on the index card C for so to do facilitates ascertaining what may be printed from the type characters as T and this expedites filing and other handling of a printing device of this general character.

I have illustrated a modified form of my invention in Figs. 4 and 5 and here I have shown a plate $P1a$ mounted on a frame Fa above the plate as Pa in contradistinction to the arrangement shown in Fig. 1 wherein the plate P is mounted on the frame F above the plate $P1$. Moreover, by reference to Figs. 4 and 5, it will be noted that while the aligned data representations Da and $D1a$ are formed in the plate $P1a$ and frame Fa , these data representations are not aligned with the type characters $T1$ to which these perforations are desirably related. Thus where, as in the instance of the printing device shown in Fig. 4, the type characters are located in one portion of the plate, the data representations may be afforded in another portion of the plate. In other respects, however, the printing device shown in Figs. 4 and 5 corresponds to that shown in Figs. 1, 2 and 3 and I have, therefore, applied reference characters to the various elements in Figs. 4 and 5 that correspond to the reference characters applied to like elements as these appear in Figs. 1, 2 and 3 except that the suffix *a* is added to these reference characters where they appear in Figs. 4 and 5.

It will be seen from the foregoing description that I have provided a printing and control device of such nature that type characters and data representations may be afforded on a single element, namely, an embossable printing plate so that therefore when it is desired to change the data that may be printed from the type characters or that represented by the perforations, it is only necessary to remove a single element from the device. It has been found that an arrangement of this character mitigates against the likelihood that a change will be made in the type characters without there being a corresponding change in the data representations related thereto and this assures accurate functioning of devices of the character to which my invention relates.

While I have illustrated and described selected embodiments of my invention, it is to be understood that these are capable of variation and modification and I therefore do not wish to be limited to the precise details set forth but desire to avail myself to such changes and alterations as fall within the purview of the following claims.

I claim:

1. A printing device including a carrier, a printing plate having type characters thereon, and means for securing said plate to said carrier, said plate and carrier having aligned perforations formed therein at predetermined positions

to afford data representations on the device whereby impressions may be made from the type characters and the data representations may be utilized to control operations related to the type characters to which such representations are related.

5 2. A printing device including a carrier, a printing plate having type characters embossed thereon, said plate and carrier having aligned perforations formed therein related to at least selected of the type characters embossed on the plate to afford representations of the data that may be printed from such type characters, and means for releasably securing said plate to said carrier whereby one such plate may be removed and another substituted therefor when a change is desired in the data that may be printed from the type characters and represented by the perforations so as to thereby insure that both the type characters and the data representations related thereto will be changed when a change is desired.

10 3. A printing device including a carrier, a printing plate having type characters embossed thereon, said plate and carrier having aligned perforations formed therein respectively in alignment with and related to at least selected of the type characters to thereby afford representations of the data that may be printed from such type characters, and means for releasably securing said plate to said carrier whereby one such plate may be removed and another substituted therefor when a change is desired in the data that may be printed from the type characters and represented by said perforations so as to thereby insure that both the type characters and the data representations related thereto will be changed when a change is desired.

15 4. A printing device including a carrier, a plurality of printing plates having type characters embossed thereon, at least one of said plates and said carrier having aligned perforations formed therein to afford representations of data that may be printed from at least selected of type characters embossed on said plate, and means for releasably securing said plates to said carrier whereby either or both of said plates may be removed therefrom so that another plate may be substituted therefor to thereby insure that when the plate having data representing perforations therein is removed from said carrier the type characters to which said perforations relate will also be removed from said carrier.
